CLAIM

The ornamental design for set of vehicle headlights as shown and described.

DESCRIPTION

FIG. 1 is a perspective view of a left upper vehicle headlight of set of vehicle headlights shown separately for ease of illustration;

FIG. 2 is another perspective view of a left lower vehicle headlight of the set of vehicle headlights shown separately for ease of illustration;

FIG. 3 is the other perspective view of a right upper vehicle headlight of the set of vehicle headlights shown separately for ease of illustration;

FIG. 4 is the other perspective view of a right lower vehicle headlight of the set of vehicle headlights shown separately for ease of illustration;

FIG. 5 is a front view of the left upper vehicle headlight shown separately for ease of illustration;

FIG. 6 is another front view of the left lower vehicle headlight shown separately for ease of illustration;

FIG. 7 is the other front view of the right upper vehicle headlight shown separately for ease of illustration;

FIG. 8 is the other front view of the right lower vehicle headlight shown separately for ease of illustration;

FIG. 9 is the other front view showing the set of vehicle headlights of my new design arranged on a vehicle;

FIG. 10 is the other perspective view showing the set of vehicle headlights of my new design arranged on the vehicle; and,

FIG. 11 is the other perspective view showing the set of vehicle headlights of my new design arranged on the vehicle.

The broken line portions of the set of vehicle headlights in FIGS. 1-11 form no part of the claimed design. The broken lines of the vehicle in FIGS. 9-11 illustrate unclaimed environment and forms no part of the claimed design. The dot-dash broken lines in FIGS. 10-11 depict a symbolic break and form no part of the claimed design.
